UNITED STATES PATENT OFFICE.

ISAAC P. TAGGART, OF PHILADELPHIA, PENNSYLVANIA, ASSIGNOR TO
ANNA E. TAGGART, OF PHILADELPHIA, PENNSYLVANIA.

AUTOMATIC DRAFT-REGULATING MECHANISM.

SPECIFICATION forming part of Letters Patent No. 714,259, dated November 25, 1902.

Application filed March 3, 1902. Serial No. 96,356. (No model.)

To all whom it may concern:

Be it known that I, ISAAC P. TAGGART, a citizen of the United States, residing at Philadelphia, county of Philadelphia, State of Pennsylvania, have invented certain new and useful Improvements in Automatic Draft-Regulating Mechanism, of which the following is a specification.

My invention relates to an improved automatic draft-regulating mechanism designed particularly for hot-water heaters. Heretofore automatic mechanisms have been devised for this purpose in which the heated water was used to expand a confined expandable medium, and thereby operate a lever mechanism connected to the draft-closures.

My improvements consist, mainly, in confining the expandable medium, preferably air, in vessels adapted to float in a circulating-chamber for the heated water at varying heights therein determined by the temperature of the water and the varying buoyancy of the vessels caused by the expansion and contraction of the confined expandable medium, as air, the weights of the connected moving parts being properly balanced by the normal buoyancy of the movable air vessels and by a suitable counterweight, as required.

The invention is fully described in connection with the accompanying drawing and is particularly pointed out in the subjoined claim.

The drawing is a sectional elevation of a simple form of apparatus embodying my invention.

A represents a circulating-tank, which is connected at points *a* and *a'*, respectively, to the hot-water heater, so as to secure a circulation through said tank which will cause a variation of temperature in the latter corresponding with that in the heater.

B B represent similar expandible air-chambers, any desired number of which may be employed. The displacement of these chambers is greater than their weight, so as to cause them to float in the water contained in the tank, their buoyancy, however, varying with the expansion or contraction of the air confined in them, due to the varying temperature of the water surrounding them and the corresponding spreading or closing of the

yielding walls *b* and *b'* of each chamber. These walls may be made of thin circularly-corrugated metal to permit of considerable enlargement of the chambers under pressure 55 of the heated air inclosed. These buoyant chambers B B are in the connected apparatus pressed down somewhat in the water-tank by the unbalanced weight of the lever mechanism connecting them with the damper 60 and draft-door—for instance, of the heater to which the apparatus is attached—a rod C, which extends through an opening in the top of the tank, being pivoted to a lever D, forming part of said connecting mechanism, as 65 shown, and bearing upon said chambers, so as to rise and fall with the latter. This lever D is fulcrumed at *d* to a fixed support and is operatively connected by any suitable means to the draft-closures of the heater, one end 70 being preferably connected to the damper and the other to the draft-door. An adjustable weight W is arranged to slide upon this lever and is adapted, in connection with the buoyancy of the air-chambers, to so 75 balance the weight of the parts as to allow said air-chambers to float in the expansion-tank, and by the variation in their buoyancy, due to different temperatures of the water therein, as stated, to correspondingly vary 80 the balance and cause an upward or downward movement of the lever D, as required to restore the predetermined operating temperature of the water. Thus if the temperature of the water falls below that desired the 85 air-chambers will be contracted, and their buoyancy being thus reduced they will sink so as to allow a corresponding movement of the lever D, producing an increase of draft, and when the resulting increase of heat in 90 the furnace has raised the temperature of the water the buoyancy of the air-chambers will be increased and a reverse movement of the balanced parts will follow, reducing the furnace-draft. Thus the latter is automatically 95 adjusted with nicety and certainty, the floating balance in which the parts are maintained insuring a quick response to very slight changes of temperature in the water and the movement of the latter, due to the 100 circulation through the tank, keeping the floating parts constantly free and ready to

adjust themselves in accordance with the varying buoyancy. At the same time the apparatus is very simple in construction and operation, easily kept in order, and readily adjusted to maintain any desired temperature.

It is evident that the apparatus specifically shown and described may be readily modified without departing from the spirit of my invention, and I do not, therefore, desire to limit myself to this particular construction; but

What I claim is—

An automatic draft-regulator mechanism for hot-water heaters comprising a hot-water-

circulating tank, one or more expansible sealed chambers adapted to freely float in said tank and containing an expansible medium, and a balanced draft-lever mechanism connected to said floating chamber or chambers and adapted to be operated by the varying buoyancy thereof due to expansion and contraction of the chamber with the contained medium, substantially as set forth.

In testimony whereof I affix my signature 25 in the presence of two witnesses.

ISAAC P. TAGGART.
